UNITED STATES PATENT OFFICE.

GEORGE W. DONNING, OF EAST ORANGE, NEW JERSEY, ASSIGNOR TO
HARRY T. AMBROSE, OF ORANGE, NEW JERSEY.

CARBON HOLDER AND SEPARATOR.

No. 826,484.

Specification of Letters Patent.

Patented July 17, 1906.

Application filed February 10, 1903. Serial No. 142,787.

To all whom it may concern:

Be it known that I, GEORGE W. DONNING, a citizen of the United States, residing at East Orange, in the county of Essex and State of New Jersey, have invented certain new and useful improvements in Carbon Holders and Separators; and I do hereby declare the following to be a full, clear, and exact description of the invention, such as will enable others skilled in the art to which it appertains to make and use the same.

This invention relates to flat-platen type-writing machines, and more particularly to devices for holding and lifting or separating one or more carbon-sheets from the platen or work and for clamping the paper which is to receive the impression to the platen, these parts being connected and having operating mechanism by means of which they may be simultaneously raised for permitting arrangement of the work or lowered and held down while the impression is being made.

The invention also relates to certain details of construction for facilitating and perfecting the operation of the above devices and greatly expediting the work of the operator.

The object of my invention is to provide simple and effective devices for holding one edge of the carbon-sheet, for clamping and holding the work on the platen, and for simultaneously raising said devices and separating the carbon-sheet through the medium of a foot-treadle, a connecting-rod, crank-levers, and other connections, for permitting the work, such as a statement-blank, to be conveniently removed from or applied to the platen in proper relation to the carbon-sheet without the necessity of handling the carbon-sheet, whereby the work is expedited and soiling of the fingers and the paper are avoided and generally improved results secured.

Another object of my invention is to provide for simultaneously raising and separating two carbon-sheets to different heights from the platen or papers which receive the impression to facilitate the insertion or removal of work.

Another object of my invention is to provide for supplying and clamping on the platen a third carbon-sheet, preferably in a transverse direction in regard to the other carbon-sheets and the paper.

Another object of my invention is to pro-

vide for winding up and removing the carbon-sheet from the face of the platen, so that the latter may be used temporarily for other work.

Another object is to provide for conveniently inserting or removing work or paper without the disadvantage of pushing the writing mechanism back to the rear of the track-frame.

Another object is to provide for vertically and simultaneously moving the tape work-holder and the carbon-sheets to different heights, so as to facilitate the insertion and removal of work, and means for keeping the tape work-holder taut when it is so raised from the printing-surface.

Another object is to provide for the positioning and movement of the carbon-sheet, which may be a manifolding paper or ribbon carbonized or otherwise provided with a transferring medium of the same color or of different colors arranged in columns or paths, or where a plurality of sheets are employed they each to be of different colors, or have their surfaces provided with columns or paths of varying colors.

I preferably support the carbon-paper or other manifolding material in a permanent fixture, such as a roll mounted on the track-frame, the platen, or table, and provide special devices, as above indicated, for holding, raising, and separating the free edge of the carbon-sheet for permitting the quick insertion and removal of the paper which receives the impression. The paper placed beneath the carbon-sheet, as well as that placed thereon to receive the first impression, must be firmly held to the platen before being written upon. For this purpose I provide certain paper-clamps, which will be hereinafter fully described.

The matter constituting my invention herein will be defined in the claims.

I will now describe the details of construction and operation of my mechanism for accomplishing the results above indicated by reference to the accompanying drawings, in which—

Figure 1 represents a perspective view of a flat-platen type-writing machine with part of the track-frame broken away and showing part of my mechanism. Figs. 1^a and 1^b represent similar views in detail of a part of the mechanism for effecting raising of the paper.

clamping device. Fig. 2 represents a similar view showing modifications in construction of the carbon-sheet clamp and its lifting mechanism. Fig. 3 represents a top plan view of the same mechanism and devices. Fig. 4 represents a side elevation of the platen and lifting devices, the track-frame being cut away on the line 4-4, Fig. 3. Fig. 5 represents a perspective view of a portion of the platen and the angular paper-clamp at one edge of the platen. Fig. 6 represents a perspective view of my type-writing machine, showing modifications of the carbon-sheet rolls (three rolls being shown) and the 15 clamping or holding devices for the free edges of the carbon-sheets. Fig. 7 represents a side elevation, on enlarged scale, of a crank-arm and connections for simultaneously raising two carbon-sheet clamps to different 20 heights. Fig. 8 represents a top plan view of the same mechanism shown in Fig. 6. Fig. 9 represents the right-hand side elevation thereof. Fig. 10 represents the left-hand side elevation thereof. Figs. 11 and 12 represent 25 detail views, on enlarged scale, of the carbon-roll shaft or spindle and a tension device therefor. Fig. 13 represents a front end elevation of the machine shown in Fig. 8. Fig. 14 represents a side elevation, on enlarged scale, of part of the platen and the 30 lifting-lever or crank-arm for the two carbon-paper clamps. Figs. 15 and 16 represent detail views, on enlarged scale, of the lower and upper clamps or holders for the edges of the 35 carbon-sheets; and Fig. 17 is a detail sectional view of the spring-actuated spool for the work-holding tape.

My invention in its more simple form embraces in a machine a single clamp for the 40 edge of the carbon-sheet and suitable mechanism for lifting such clamp and at the same time lifting a paper-clamp from the platen or work which is placed on the platen. This form of machine is illustrated in Figs. 1 to 5, 45 inclusive.

The track-frame A (on which travels the writing mechanism B, having a forward and backward movement for line-spacing and also lateral movement for letter-spacing) is 50 disposed upon the hinged plate a, which rests upon the table, (the sides of the said frame being perforated to receive a pin a^x , which passes through a standard a^{xx} , as shown in Figs. 1 and 2,) and within the frame A the platen C is hinged at c and otherwise supported in the usual manner, as clearly shown in 55 Figs. 1, 2, and 3. A transverse space a^2 is provided between the platen and the front of the frame for application of devices not here shown. The carbon-sheet X is preferably wound upon a roller E on the shaft e, which is supported in suitable bearings in the brackets a'. The carbon-sheet is drawn over 60 the platen and is held at its front free edge by the clamping device D, which is shown in per-

spective in Fig. 16, and is composed of the relatively stationary member d' and the swinging member d , which parts are pivotally connected or hinged at d^3 . The opposite ends may be hinged or locked by the 75 spring-catch d^2 . The swinging member d is preferably provided at its inner face with the inward-projecting pins or teeth d^4 , and the other member d' may have holes or depressions, as shown in Fig. 16, for adapting 75 the parts to better hold the carbon-sheet. The stationary member d' of the clamp D is connected to the outer end of the crank arm or lever F, as shown in Figs. 1, 3, and 4. The carbon clamping and holding device D is located at or above the plane of the upper surface of the platen in order to prevent the carbon from being drawn down sharply over the front end of the platen, and to this end the clamp is preferably disposed upon the platen. 80 The mechanism for raising the clamp D and the paper-clamp K will now be described.

The crank arms or levers F and f' , forming one piece, are mounted on a rock-shaft f , which is supported in a suitable fulcrum 90 member or bearing f^2 , as shown in Fig. 1. To the rear end of the arm f' is pivotally connected the connecting-rod G, which at its lower end is connected by a hook-and-staple connection g to the treadle H, which is hinged 95 by a pin h to the floor-bracket G'. A spring f^x , connecting with the lever F and the platen or other appropriate part, tends to exert a pull upon the lever F to reposition it after it has been operated. The crank-arm 100 F extends forward and parallel to the side of the platen and is made one of the members of a pair of lazy-tongs. The second member I of this device is provided near the middle with an elongated opening or slot, (see 105 Fig. 1^b), through which is passed a rivet f^3 , secured in the crank-arm F for connecting the parts together. The forward end of the member I is passed through an opening in the post i, which is secured to the table and is 110 provided at its lower end with a coiled spring and at its upper end with an adjusting-screw for supporting the outer end of the member either in a higher or lower position. To the ends of the members F and I is connected 115 pivotally at i and f^4 the angular clamping device K, which fits over the edge of the platen, as shown more clearly in Fig. 5. This clamp K is L-shaped in cross-section, and the horizontal portion thereof is provided at its under side with flat spring-pressers k for more securely holding the papers in 120 place on the platen. The vertical portion of the clamp K is provided with inward-projecting stop-pins k' , as shown in Fig. 5, for bearing against the under side of the platen when the clamp is raised. The vertical portion of the clamp K may also be utilized as a work stop or guide for feeding work up 125 against it to insure perfect alinement. A 30

coiled spring may connect with the arm F and the table for holding down the clamps D and K. In order to allow for the adjustment of the paper-clamp K to suit various thicknesses of paper, the forward end of the member I of the lazy-tongs is passed through a vertical slot in the post i, where it is pressed upward by the coiled spring i' against the setscrew i². It will be understood that a raising or lowering of the screw will cause the rear end of the clamp to raise or lower with reference to its forward end or the arm F. A partial rotation of the rock-shaft f by means of the treadle H, the connecting-rod G, and the crank-arm f' will raise or lower the free ends of the lazy-tongs and through them the clamp K and the carbon holder or clamp D. The clamp D may be secured at one end directly to the outer end of the crank-arm F or to any convenient part of the paper-clamp K, and two or more of these carbon-paper clamps may be provided and operated, as will be hereinafter more fully described by reference to Figs. 6 to 16, inclusive, of the drawings. The lazy-tongs device above described may be omitted and the clamp-piece K connected directly to the lever-arm F, as shown in Figs. 3 and 4. In this construction the outer end of the lever-arm is curved inward and has connected to it the carbon-paper clamp D. In this construction the swinging member of the clamp D is pivoted at d³ to the fixed member, so as to be swung outward in a horizontal position, and the outer end of said member is slotted and engaged by a pin d³, as shown in Fig. 3. In this construction also the flat presser-springs k, applied to the under side of the clamp K, come more prominently into use—that is, the presser-springs k are more advantageous in this construction of the connection from the lever-arm F to the clamp K.

In addition to the clamping devices above described I provide work-holding tapes L, which are connected at their inner ends to sleeves l, arranged to slide transversely on the rods l', which are secured in the side brackets a', as shown in Figs. 2 and 3. The spool or sleeve l is preferably provided internally with a coiled spring l² for holding the tape L in tension and taking up any slack thereof when the front end is raised. The front end of the tape L is connected to a slide l' on the clamp D, as shown in Figs. 2 and 3. By means of the sliding parts l and l' the tape L may be readily moved over the work to the right or left and will serve for holding the paper and carbon-sheets flat on the platen.

In Fig. 1 the statement-blank W is shown in position on the platen with one corner w turned up to show the carbon-sheet X below. Another part of the statement-blank will be inserted below the carbon-sheet. In Fig. 2 the statement-blank W is shown partly inserted in position.

A paper guide or gage b, Fig. 1, is secured to the edge of the platen C for guiding the paper when it is adjusted for receiving the impression. The guide b may be placed at either edge of the platen and two or more thereof may be used, and also an adjustable guide may be used, as described in a separate application for patent.

The second carbon-roller E' is mounted by its shaft e' in the side brackets a', as shown in Figs. 6, 8, 9, and 10, and has wound upon it a second carbon-sheet, which at its front edge is held by the lower clamp M, Figs. 7 and 15. This lower clamp, like the clamp D, is located in the general region of the surface of the platen in order to obviate the sharp bending of the carbon-web, which occurs at the front of the platen when the front holder is disposed below the platen. In case two carbon-rollers are used both sheets of carbon-paper are drawn over the platen and are held at their front free edges in the clamps D and M. Certain tension devices e², preferably in the nature of adjustable cone-shaped bearing-pintles provided with lock-nuts, are provided for the shafts e and e' of the carbon-rollers, as shown in Fig. 8 and more particularly disclosed in my concurrently-pending application, Serial No. 143,421, filed February 14, 1903. The upper carbon-paper clamp D is substantially the same in construction as that above described and shown in Fig. 16. The lower carbon-paper clamp M is shown on enlarged scale in Fig. 15 and is composed of the relatively fixed member m and the swinging member m', which is pivotally connected or hinged at m² to the fixed member, as shown in Figs. 8 and 15. A sliding collar m³ is adapted for sliding over and holding the swinging member m' to the fixed member. This clamp M is in the nature of a split rod. Both of these clamps are connected to the forward end of the crank-arm P, as shown in Figs. 7 and 14. The crank-arms P and p' are fixed on a rock-shaft p, as shown in Figs. 8 and 9, and in practice are pivotally connected by a pin to a connecting-guide p², which will connect with the foot-treadle H, pivoted to a floor-bracket G', as shown in Figs. 1 and 2. The lever-arm P is provided at the front end with a turned-up portion p³, in the upper end of which is provided a slot p⁴ for receiving the outer end of the clamp M. A post p⁵ is also secured to the forward end of the lever-arm P for connecting with one end of the clamp D, as shown in Fig. 7. As the rock-shaft p is partly rotated by pressure on the foot-treadle the outer end of the lever-arm P will be forced upward, thereby first raising the clamp D, while at the same time the other clamp M remains stationary until the turned-up end p³ of the lever P has been forced upward a distance equal to the height of the slot p⁴, when the clamp M will be forced upward. It will be understood that

the clamp M is not raised until the bottom of the slot p^1 bears against it, when it will be raised a sufficient distance to separate the lower carbon-sheet from the paper and platen. The upper carbon-sheet engaged by the clamp D will be raised to a greater height than the lower carbon-sheet engaged by the clamp M, so that both carbon-sheets will be separated from each other and from the paper, thereby permitting the sheets of paper to be readily removed or inserted between and below the carbon-sheets.

At the left-hand side of the platen, Figs. 8 and 13, are suitably mounted the spring 15 per-clamps N, which are secured to the rod n, having coiled springs n' for forcing the edges of the clamping-plates N in contact with the paper. A suitable handle for operating the clamp N is provided at the front 20 end of the platen, as shown in Figs. 8 and 13. The work-holding tape L, Fig. 8, is supported and operated as above described.

As shown in Fig. 6, the carbonized sheet may be in different colors—that is to say, 25 each sheet may have a column or columns of color different from that of the body of the sheet—or there may be transverse paths of different colors. There may be stripes of different colors lengthwise or crosswise of the 30 sheet. In other words, it may for billing work, for instance, be desirable to have a narrow red stripe located approximately where it will be upon the credit-column of the statement-blank. By this means the credit 35 amounts would appear in red on the duplicate sheet of the statement-blank just as on the original, as produced by the red ribbon of the type-writer.

It may be that sometimes an extra carbon 40 copy would be desired, as where billing is being done in connection with a statement-blank, and a third copy is required. To this end a second carbon-sheet may be used, operating the same as the first, as described, 45 and a paper-roller.

A paper-roller R may be secured to a shaft r, Figs. 8, 10, 11, 12, and 13, which is suitably supported in the journal-bearings s s'. The shaft r may be made hollow and will be supported at one end on the tapering pintle s² in the journal-box or bracket s, as shown in Fig. 12. The other end of the shaft r has seated in it a screw s⁴, upon which is placed a sleeve s⁶. This sleeve rests in the journal-box s' and is provided with a circular groove r', into which is placed a set-screw s⁵, for providing the proper tension on the shaft r. A thumb-nut s³ is applied to the outer end of the screw s⁴. By removing the thumb-nut 50 and the set-screw s⁵ the shaft r may be removed from its bearings for winding upon it a sheet of paper or carbon, or for removing from it the old sheet. As it will be seen by reference to Figs. 8 and 10, the roller R is placed at one side of the platen and parallel

to the edge thereof, so that the sheet may be drawn transversely across the platen, and in practice it will be the lowermost sheet which is used in connection with the carbon-sheets, which are wound upon the rollers E and E'. 70 The sheet V, Figs. 8 and 13, is drawn transversely across the platen, and its outer free edge is held down on the platen by the clamping-plate T, which is secured to a rod t, supported in the bearings u, and which is provided with coiled springs t' for pressing the plate down upon the platen or carbon-sheet. The rod t is provided at one end with a handle t² for raising the clamp-plate. The edge of this plate is made sharp, so that the sheet 80 may be readily torn off and detached. The sheet V may at any time be drawn forward across the platen by hand for exposing fresh surfaces thereof to the type. The clamp T, being at one edge of the platen, is out of the 85 way of the longitudinal carbon-sheets, a statement-blank, or other paper which is inserted on the platen.

The parts being constructed and arranged as above described, the operation is very simple, and most of the parts will be operated by the foot through the medium of the treadle H, the connecting-rod G, and the lever-arms mounted upon the rock-shaft, as above described. If required, the carbon-sheets 90 when worn out or deteriorated may be released from the clamping-lever D and slightly drawn forward and again secured in the clamps, so as to present fresh surfaces to the type, the forward edges of the sheets which project slightly by having been thus drawn forward, being cut off at the clamps. Very little handling of the carbon-sheets will be required, and since they are raised and lowered by foot-power the hands of the operator 105 will be free for handling the statement-blanks or other papers to be removed and inserted in position for receiving the impression.

As shown in Figs. 1, 2, and 3, the statement-blank W is a loose unattached folded 110 sheet comprising an upper and a lower member and is inserted by hand, the upper member being separated from its attached lower member sufficient to permit of its being positioned over the upper surface of the carbon-sheet X, while the lower member is positioned below this, the carbon-sheet thus being interposed between the two members. To permit of this being done, the forward end 115 of carbon-sheet is raised by the mechanism above described, as well the retaining device for holding the statement-blank against the surface of the platen. With the form of device illustrated in Figs. 7 and 8, this unattached billing-form is employed in connection with a supplemental sheet V, continuously carried on the paper-roller R, in which event an extra carbon-sheet is employed, the same being carried by the carbon-paper clamp M. This carbon-paper clamp M and 120

the carbon-paper clamp D (carrying the carbon-sheet which is to be interposed between the two members of the billing-form W) are so arranged as to have their forward ends 5 raised to different heights, so that the upper carbon-sheet is positioned higher than the lower. This permits the free insertion and withdrawal of the billing-form W in operative relation to the upper carbon-sheet without disturbing the lower carbon-sheet.

By means of these devices and the method of operating them the operator is saved the inconvenience of soiling his fingers and from soiling the paper sheets, and his work is 15 greatly expedited.

Having thus fully described my invention, what I claim, and desire to secure by Letters Patent, is—

1. In a type-writer, a flat platen, a carbon 20 element feedable over the platen, a carbon-holder disposed at one edge of the platen, a fulcrum member constructed and arranged independent of the carbon-holder, a tilttable lifting element for said holder fulcrumed in- 25 termediate of its ends on said fulcrum mem- ber and connected at one end with said car- bon-holder and readily-accessible operator- actuated means located in a plane below the 30 platen and connected with the other end of said element for effecting raising of the car- bon-holder.

2. In a type-writer, a flat platen, a track- 35 frame disposed contiguous thereto, a carbon element, a carbon-holder, a rocking lever upon which said holder is supported and ful- crumed intermediate of its length and con- 40 structed to be rocked independent of the track-frame to raise and lower the carbon- holder and readily-accessible operator-actu- ated means disposed in a plane below the 45 platen and connected with said lever on the other side of its fulcrum from said holder for effecting raising of the latter.

3. In a type-writer, a flat platen, a track- 45 frame disposed contiguous thereto, a lever of the first order, a carbon-holder supported on said lever at right angles to the length of said lever, said lever being operable independent of the track-frame and constructed to elevate 50 and lower the carbon element away from and back to the platen and readily-accessible operator-actuated means located in a plane below the platen and connected to said lever for effecting raising of the carbon-holder.

55 4. In a type-writer, a flat platen, a track- frame, a rocking lever tilttable independent of the platen and track-frame, a carbon- holder supported at right angles on said lever, and a pedal device disposed in a plane 60 below the platen and connecting with said lever and constructed to rock said lever to position said carbon-holder above the platen.

5. In a type-writer, a platen, a track- frame, carbon elements, a carbon-holding de- 65 vice comprising a plurality of members dis-

posed and operating independent of the track-frame and engaging the forward edges of the carbon elements, and means for elevating the carbon-holder away from the platen and simultaneously separating the 70 carbon-holder elements, and for returning the same to normal position, substantially as described.

6. In a type-writer, a platen, carbon ele- 75 ments, means for supporting the carbon ele- ments at the rear, a carbon-holding means for retaining the unwound ends of the carbon element and comprising a plurality of mem- bers, means for elevating the carbon-holding mem- bers together and effecting a separation 80 of these members when elevated, and writing mechanism movable over the platen and oper- able at any predetermined point with refer- ence to the same and independent of the ac- tuation of the carbon-elevating means, sub- 85 substantially as described.

7. In a type-writer, a flat platen, a carbon- holder disposed and operable independent of the platen, manifolding material carried by and operable with said holder and having 90 stripes or paths of different colors, a fulcrum member, a rocking lever pivoted intermediate its length on said fulcrum member and connected at one side thereof with said car- bon-holder, and operating means connected 95 with said lever at the other side of said ful- erum member.

8. In a flat-platen type-writing machine, the 100 combination with the platen, of a clamping and holding device for one edge of the carbon- sheet, a lifting-lever connecting with said clamp, and means for operating the lever to raise the clamp, and separate the carbon- sheet from the paper or platen, substantially as described.

105 9. The combination with the platen, of a carbon-sheet clamp and a paper-clamp, of lifting devices connecting with both of said clamps, and operating mechanism whereby both of said clamps may be simultaneously raised and the carbon-sheet separated from the paper, substantially as described.

110 10. The combination with the platen, of a clamping device for one edge of the carbon- sheet, a lever on a rock-shaft and connecting 115 at one end with said clamp, a foot-treadle and a rod connecting it with the other end of said lever for raising and separating the car- bon-sheet from the paper or platen, substan- tially as described.

115 11. The combination with the platen, of a carbon-sheet clamp and a paper-clamp, an operating device connecting with both clamps, and mechanism for simultaneously raising both clamps, effecting separation of the sheets held thereby, and releasing the paper from the platen, substantially as described.

120 12. The combination with the platen, and track-rails, of a paper-clamp operable inde- 125 pendent of the tracks, a lever connecting

- therewith, and a foot-treadle and connections to said lever for raising and lowering said clamp to release or hold the paper on the platen, substantially as described.
13. The combination with the platen and a track-frame, of a paper-clamping device arranged independent of the track-frame and adapted to bear on the platen, a pivoted arm connecting therewith, and a lever-operated device disposed contiguous to the platen, at the edge thereof, and engaging said arm to operate the same on its pivot and effect an elevation of the clamping device, substantially as described.
14. The combination with a platen, of a track-frame, a plurality of clamping devices normally resting upon the platen and disposed independent of the track-frame, a rocking lever, a connection engaging said lever and one of said clamping devices, centrally, and means for rocking said lever to raise said clamping device to a predetermined height above the platen, substantially as described.
15. The combination with a platen, of a track-frame, a plurality of clamping devices normally resting upon the platen and disposed independent of the track-frame, a rocking lever, a connection engaging said lever and one of said clamping devices, centrally, means for rocking said lever to raise said clamping device to a predetermined height above the platen, and means constructed to regulate movement of said clamping device to effect its proper positioning, substantially as described.
16. The combination with a platen and a track-frame, of a paper-clamping device and a carbon-sheet-clamping device, independent of the track-frame, lever-operated means connecting with each clamp for effecting operation thereof, substantially as described.
17. The combination with a platen and a track-frame, of a paper-clamping device and a carbon-sheet-clamping device, independent of the track-frame, lever-operated means connecting with each clamp for effecting operation thereof, and means for limiting the extent of movement of said clamping devices, substantially as described.
18. The combination with a flat platen, of carbon elements, a carbon-sheet-clamping device comprising a plurality of members for engaging edges of the carbon elements, a connecting-lever device for raising said members of the clamping device to different heights relative to each other to effect separation of the carbon elements from the paper and platen.
19. The combination with a flat platen, a paper-sheet supporting and positioning device disposed contiguous to the platen, a carbon-sheet-clamping device, a lever device connecting with said clamping device, and an operating device for raising the clamping device independent of and away from the paper for effecting separation of the carbon-sheet from the paper element.
20. The combination with a platen, of a carbon-element roller device mounted near the rear end of the platen, a clamping device adapted to engage and hold the free edge of the carbon element, and lever-operated mechanism connecting with the clamping device for operating the same to raise the carbon away from the platen and effect a separation of said carbon from the work-sheet, substantially as described.
21. The combination with a flat platen, of a roller device disposed parallel to one side thereof and carrying a sheet positioned across the platen, a normally fixed fulcrum member, a sheet-holding device, and a lifting device mounted on said fulcrum and operatively connecting with said sheet-holding device at one side thereof, and operating means connected with said lifting device at the other side of said fulcrum whereby, when said lifting device is operated, the sheet is separated from the platen, substantially as described.
22. In a type-writer, a flat platen, a track-frame, a carbon-carrying element disposed and operating independently of the track-frame and arranged when elevated to descend automatically toward the platen, a rocking lever fulcrumed intermediate its length and connected with said carbon-carrying element at one side of its fulcrum, and operator-actuated means disposed in a plane below the platen and connecting with said lever on the other side of its fulcrum for effecting lifting of the carbon-carrying element away from the platen, substantially as described.
23. In a type-writer, a flat platen, a track-frame, a fulcrum upon which said frame tilts, a carbon-carrying member, a fulcrum therefore independent of the fulcrum of the tiltable track-frame, and means for effecting movement of said member independent of the track-frame, said member being constructed to gravitate toward and upon the platen independent of said moving means, substantially as described.
24. In a type-writer, a flat platen, a track-frame, a tiltable carbon-carrying member disposed independent of the track-frame, a tension device constructed normally to pull said member in a direction opposite to its tilting movement, and means for tilting the member away from the platen against the action of said tension device, substantially as described.
25. In a type-writer, a flat platen, a track-frame, a tiltable carbon-carrying member disposed and operable independent of the track-frame and spring-actuated to cause its movement toward and upon the platen, a rocking lever device fulcrumed independent of the track-frame for effecting elevation of said car-

bon-carrying member independent of the frame, and a lever-operating device connecting with said lever, substantially as described.

26. In a type-writer, a platen, a carbon element, a clamp and carrier for the forward edge of the carbon element disposed in the general region of the surface of the platen, a rocking member for elevating the same away from the platen, means for operating said rocking member, and means for guiding a work-sheet across the platen, substantially as described.

27. In a type-writer, a platen, a carbon element, a clamp for the forward edge of the carbon element, a rocking member for elevating the same away from the platen, means for actuating said rocking member, and a work-holder disposed contiguous to, and coöperating with, the platen, substantially as described.

28. In a type-writer, a platen, a carbon element, a holder device for the forward edge of the carbon element, a lifting member for elevating the same away from the platen, means for actuating said lifting member, a work-holder disposed contiguous to, and coöperating with, the platen, and a combined work-holder and guiding device operated by said actuating means, substantially as described.

29. In a type-writer, a platen, a carbon element, a holder device for the forward edge of the carbon element, a lifting member for elevating the same away from the platen, means for actuating said member, a work holder disposed contiguous to, and coöperating with, the platen, and a combined work holder and guiding device, and an independent guiding device, substantially as described.

30. In a type-writer, a platen, a carbon element, a holder device for the forward edge of the carbon element, a rocking member for elevating the same away from the platen, actuating means for said member, a work-holder disposed contiguous to, and coöperating with, the platen, and a combined movable work holder and guiding device operated by said actuating means, and an independent, adjustable guiding device, substantially as described.

31. In a type-writer, the combination with a flat platen, a carbon element, means for holding the forward end of the carbon element, a lifting member for raising said holding means, an actuating device therefor, a rotatable holding element engaging the opposite end of the carbon element, and an end-thrust tensioning device engaging said rotatable holding member to govern the speed of rotation thereof, substantially as described.

32. In a type-writer, a flat platen, a carbon element feedable over the platen, a carbon-clamp extending over the platen, a lifting member coöperating with the carbon-holder to effect movement of the carbon element

away from, and back to, the platen, and actuating means for said member, substantially as described.

33. In a type-writer, a flat platen, a carbon element, a combined carbon-clamping, work-holding and work-guiding device, a lifting member engaging therewith for effecting simultaneous movement of the same away from and back to the platen, and operator-actuated means disposed in a plane below the platen for effecting lifting of the lifting member.

34. In a type-writer, a flat platen, a carbon element, a combined carbon-holding, work-holding and work-guiding device, a lifting member engaging therewith for effecting simultaneous movement of the same away from and back to the platen, operator-actuated means disposed in a plane below the platen for effecting lifting of the lifting member, and independent work-holding devices coöperating with the platen.

35. In a type-writer, a flat platen, a combined carbon clamp and carrier and work-holder disposed in the general region of the surface of the platen, a lifting member engaging therewith for effecting simultaneous movement of the same away from, and back to, the platen, and a lifting-member-actuating device, substantially as described.

36. In a type-writer, a flat platen, a track-frame, a combined carbon clamping and carrying and work-holding device disposed in the general region of the surface of the platen, a lifting member engaging therewith for effecting simultaneous movement of the same away from, and back to, the platen, such movement being performed independent of the track-frame, and an actuating device for said member, substantially as described.

37. In a type-writer, a flat platen, a carbon-holding device constructed to be moved toward and away from the platen, and a foot-lever-operating means in a plane below the platen for effecting movement of the carbon-carrying device, substantially as described.

38. In a type-writer, a flat platen, a carbon-holding device constructed to be moved toward and away from the platen, a foot-lever in a plane below the platen, and intermediate mechanism connecting with the carbon-holding device, substantially as described.

39. In a type-writer, a flat platen, a carbon-holding device constructed to be moved toward and away from the platen, a foot-lever-operating means in a plane below the platen for effecting movement of the carbon-carrying device, and means for limiting movement of the foot-lever, substantially as described.

40. In a type-writer, a flat platen, a combined work holding and guiding device constructed to be moved toward and away from the platen, and foot-lever-lifting member disposed in a plane below the platen and con-

necting with said device, and actuating means for said lifting member, substantially as described.

41. In a type-writer, a flat platen, a combined work holding and guiding device constructed to be moved toward and away from the platen, foot-lever-lifting device disposed in a plane below the platen and connecting with said device, and means for limiting movement of said lifting device, and actuating means for said lifting member, substantially as described.

42. In a type-writer, a flat platen, carbon clamping and carrying and work-holding members arranged in juxtaposition one with the other, a single lifting member for effecting coöperation and simultaneous movement of said members away from, and back to, the platen, and an actuating device for said lifting member, substantially as described.

43. In a type-writer, a flat platen, a carbon-carrying device, a work-holding device, a lifting member for elevating, and changing the relative positions of, said devices, and an actuating device for said member, substantially as described.

44. In a type-writer, a flat platen, a carbon-carrying device constructed to be elevated

away from one portion of the platen, a work-holding device constructed to be elevated 30 away from a different portion of the platen and to a plane different from that assumed by the carbon-carrying device, and a single means for effecting simultaneous movement of the carbon-carrying device and of the work-holding device whereby one of said devices is elevated to said different plane from that to which the other of said devices is elevated, substantially as described.

45. In a type-writer, a flat platen, a carbon-carrying device comprising a plurality of members, means engaging said members and constructed to actuate said members to different planes relative to each other and to the platen, and work-holders deriving movement 45 from the actuation of said members and their actuating means and constructed to be actuated thereby away from the platen, substantially as described.

In testimony whereof I affix my signature 50 in the presence of two subscribing witnesses.

GEORGE W. DONNING.
